BOX BLANK FOLDING MECHANISM

Melvin H. Sidebotham, West Newton, Mass., assignor to Specialty Automatic Machine Company, Medford, Mass., a corporation of Massachusetts

Application July 2, 1934, Serial No. 733,353

27 Claims.

(Cl. 93—41)

This invention relates to the manufacture of paper or paste-board boxes, and has particular reference to the production of corrugated paper cartons in flat condition with the opposite edges of the blanks in abutting relationship, and with said edges held together by adhesively secured tape.

Various attempts have been made to produce machines for folding corrugated paper blanks in a manner to bring opposite edges thereof into juxtaposition and apply adhesive tape to such edges, but so far as I am aware, none have been a commercial success. Such machines of a prior type which act to effect the folding progressively, as by means of inclined rods or twisted belts, the blanks travelling while being folded, seldom bring the edges of the blanks into accurate abutting relationship because the stiff nature of the blanks and the irregularity of their surfaces cause a crowding back of the fold lines out of straight lines. In other machines for similar purposes the structure has been such that it has been impossible to adjust the machines quickly to adapt them for operation on blanks of different shapes and sizes.

One of the objects of my present invention is to produce a machine of the character referred to in which the blanks are forwarded from the supply feed at a speed fast enough to effect rapid production, but in which each blank comes to rest for a short period while its opposite edges are being folded.

Another object is to provide a machine for folding corrugated paper blanks having means for crushing the blanks along the lines where the folds are to be made, to reduce the thickness of the blanks along those lines and thereby aid in controlling the folds and causing them to be even and straight along the crease lines.

Another object is to provide a machine for folding corrugated paper blanks, in which the folding is effected by members which are hinged so close to the points where the creased lines of the blanks are located that the said folding members, as they swing up and over and down, will hug closely to the sections of the blanks that are being folded.

Another object is to provide means for preventing backward drag of the marginal or side portions of the blanks, serving especially advantageously when the blanks are wider than they are long.

Another object is to provide an improved taping mechanism controlled by an automatic clutch so that when the edge of a blank passes a given

point, the tape feeding rolls are thrown into operation and the tape is fed out at the same speed as the speed of travel of the folded blank, is laid on the seam in the proper position, and cut to the proper length.

Another object is to provide a machine of the character described, with improved supply feeding mechanism, in which the blanks are fed from the bottom of a pile in a hopper, to intermittently-driven blank-carrying chains, and ensure proper engagement of the pushing members carried by the chains with the rear edges of the blanks.

With the above-mentioned objects in view, and others hereinafter described, my invention consists in the construction of the machine and the combinations of elements thereof, substantially as hereinafter described and claimed.

Of the accompanying drawings:

Figure 1 is a right-hand side elevation of the machine.

Figures 2, 3 and 4 are perspective views illustrating successive conditions of the work done by the machine.

Figure 5 is a plan view of the machine partly broken out.

Similar reference characters indicate the same or similar parts in all of the views.

The frame of the machine includes main side members 30, and the main shaft 31 (Figs. 1, 5 25 and 23) is mounted in suitable bearings therein. Carried by the shaft 31 is a pulley 32 for a driving belt, suitable clutch mechanism being employed to connect the pulley to said shaft or disconnect it therefrom. Secured to the outer 30 end of the shaft 31 is a hand wheel 33. A hand lever 34 controls the clutch.

Near the other end of the shaft 31 is a pinion 35 meshing with a gear 36 carried by a shaft 37 parallel with the shaft 31 and mounted in 35 suitable bearings supported by the frame members 30 (Figs. 5, 23 and 28).

40 A sprocket 38 carried by the shaft 37 engages a sprocket chain 39 which, in turn, drives a sprocket 40 carried by a lower shaft 41 and a sprocket 42 carried by an upper shaft 93. The parts which are operated by the shafts 41, 93, will be described hereinafter.

45 Contained in a casing 44 (Figs. 21, 23, 24) is mechanism similar to that illustrated and described in Letters Patent No. 1,393,219 issued October 11, 1921, to Geo. P. Hohl, said mechanism being for the purpose of transmitting rotary motion from the shaft 37 to a shaft which actuates the blank-carrying chains presently described, so that the blanks which are fed to the 50 chains will be pushed along in an intermittent manner and will come to rest at certain timed periods. This mechanism similar to the said Hohl patent includes a gear 46 eccentrically carried by the shaft 37, a gear 47, and an intermediate gear 48. The gear 47 is carried by a shaft 49. The three gears 46, 47, 48, are held in mesh by compound links 50, 51. Due to the driving gear 46 being mounted eccentrically on the shaft 55 37, a swinging motion as well as a rotary motion is imparted to the gear 48, forcing it to swing partially around shaft 49. When the swing of the eccentrically mounted gear 46 occurs, the 60 swinging motion imparted to the gear 48 so affects the rotary motion of the shaft 49 as to cause said shaft to vary in speed from zero, up to a high speed, and then slow down again. As will be explained, this practically controls the speed of operation of all parts of the machine. It is 65 70 to be understood however that any other mechanism for variably controlling the speed of operation may be substituted for such variable-speed mechanism as illustrated in Figures 21 and 24.

Carried by the shaft 49, at its other end (Fig. 75 23) is a gear 51* meshing with a gear 52 of a

shaft 53. Said shaft carries two sprockets 54 and an intermediate sprocket 55. In practice, however, I prefer to include two intermediate sprockets 55.

5 Mounted on the sprockets 54 are chains 56 (Figs. 1, 5, 21, 28) carrying individual blank-pushing lugs 57. The other ends of the chains 56 are supported by idly-mounted sprockets 58 (Fig. 7) under that portion of the machine which may be termed the entrance end because the blanks are fed to the chains at that end as will be described.

10 The upper stretches of the pushing chains 56 are caused to travel in a uniform plane by guide strips 59 having side walls 60 the inner faces 15 of which are longitudinally grooved to receive lugs 61 (Fig. 20) of the pushers 57, whereby said pushers are guided in accurate paths.

15 The guides 59 are supported at suitable intervals by fixed cross bars 62, and are laterally adjustable thereon by mechanism to be described, to provide for operation on different widths of blanks.

20 The cut and creased blanks *a* of the type illustrated in Figure 2 are supplied singly and successively to the chains 56 by feeding mechanism which will be described hereinafter, and each blank that is then pushed along by the lugs 57 travels at diminishing speed and stops at an intermediate point of travel, to be folded to the 25 condition illustrated in Figure 3, and then resumes accelerated speed. Such changes of speed are due to the mechanism of the type explained in connection with Figures 21 and 24, contained in the casing 44.

30 Each blank pushed along, first passes between rolls which serve to somewhat crush it along both sides of the two creased lines on which it is to be folded, as illustrated in Figure 13. For this purpose there are two lower rolls 63 (Figs. 8 and 12) and two upper rolls 64. As illustrated in Figure 35 13, the rolls 63, 64, are of such width as to effect compression along both sides of the previously formed creases *a'* in the blanks (Fig. 2). The upper rolls are idly mounted in suitable bearings 40 supported by a duplex cross bar 65, and each lower roll 63 is fixed to a stud shaft 66 mounted in a bracket 67 supported by one of the chain-guide strips 59 (Figs. 7 and 8).

45 Each stud shaft 66, at its other end, has a 50 sprocket 68 (Figs. 8 and 12) engaged by a chain 69 which runs over a guide sprocket 70 and is driven by a sprocket 71 (Figs. 1 and 9) carried by the same stud shaft which has the sprocket 55 58. One of the stud shafts 66 also has a pinion 72 (Fig. 8) engaging a pinion 73 carried by a shaft 74 mounted in suitable brackets 75 and having at one end a cam 76 the purpose of which will be described hereinafter.

55 At about the mid-width of the machine (Figs. 5 and 8) a block 77 is fixedly supported by the duplex cross bar 65. Right and left hand screw rods 78 have their inner ends mounted in the block 77 and their outer ends in the frame members 30. The two screw rods 78 engage threaded 65 apertures in two blocks 79 which carry the pressing rolls 64 heretofore described, said blocks 79 being thereby adjustable along the duplex rod 65.

60 Secured to the bottoms of the blocks 79 (Fig. 7) and extending along the machine above and close 70 to the blank-carrying chains 56, are two thin strips 80 of metal. The two strips 80 overlie the side walls 60 of the chain-guiding strips 59 (Figs. 5, 8, 16 and 17) and are thereby held in proper 75 positions although their ends are free. The outer

edges of the two strips 80 are very thin and are straight, and act as guides to maintain the blanks accurately while being folded as presently described. For operation, of course, said strips are adjusted so that the straight thin outer edges thereof will be in line with two of the crease lines of the blanks fed thereto. In other words, they will be in line with the mid-width of the partially crushed lines effected by the rolls 64 (Fig. 13) hereinbefore described. The fact that the crushed lines are wider than the creased lines of the blanks facilitates accurate control of the lines of fold by the thin edges of the strips 80. The function of said strips 80 is illustrated by Figures 16 and 17.

The mechanism which folds each blank as illustrated by the curved dash lines in Figure 2, to convert it to the condition illustrated by Figure 3 will now be described.

20 Mounted in bearings provided in lugs projecting from the outer faces of the side walls 60 of the guides for the blank-carrying chains, are two rock shafts 81 (Figs. 1, 5, 16, 17, 19, 21). Each shaft 81 carries arms 82 clamped thereto, said 25 arms having folder acting wing plates 83 the edges of which that act on the blanks being slightly curved to act smoothly in the blanks. Each shaft also has a pinion 84 (Fig. 18) meshing with a rack 85 vertically slidable in ways in a 30 bracket 86 secured to a chain guideway 59, the lower end of the rack being connected by a link 87 with an arm 88 of a rock shaft 89. Said shaft 89 also has an arm 90 (Fig. 1) carrying a roll 91 and acted upon by a cam 92 carried by shaft 93. 35 A spring 94 is illustrated to effect return movement of the arm 90, but obviously the roll 91 might enter a cam groove in one face of a disk carried by the shaft 93.

The rocking of the shaft 89 effects, through its 40 two arms 88, a simultaneous swinging movement of the folders 82, 83, from the positions shown in Figure 16 to the positions shown in Figure 17 and back again. The complete inward and return movements are very short in time, and the inward movement occurs while the blank is momentarily at rest. Therefore there is no forward urging of the blanks during the actual folding operation such as is effected by prior machines which fold progressively; that is, which push the 45 blanks along while portions thereof are being folded. In such machines there are usually some parts or members which cause a frictional backward drag on the portions of the blanks that are being folded, and which therefore tend to prevent the meeting of the edges of said folded portions in close parallel relationship. To aid in effecting such parallel relationship, and attain the production of a square fold, I provide the following structure.

50 Rigidly supported by two cross bars 95 indicated in Figure 1, is a horizontal compound T-bar 96 (Figs. 7, 16, 17, 21, 28) which, by means of stiff lugs 97, fixedly supports an aliner and separator 98 for the edges of the blanks which 55 approach each other as they are folded. In practice, said aliner is so supported that it may be laterally adjusted to ensure its lower edge, which is thin, being in the position where the edges of the particular blanks being folded, are to meet. 60 While each blank is momentarily stationary, its side portions are folded on its crease lines a^2 (Fig. 2) to bring its edges a^2 into close relationship (Fig. 3). The aliner 98 also acts to separate 65 said edges from each other to prevent them from

overlapping if a blank that has been inaccurately cut and creased is being operated upon.

To prevent the edges a^2 from lifting when the wing plates 83 rise from the positions shown in Figure 17, the aliner and separator 98 has flat 5 spring strips 99 secured to both faces thereof, to serve as catches for the folded edges of the blanks. The aliner is provided with openings 100 (Fig. 7) over which the lower ends of the flexible catches extend and into which the lower portions of the 10 catches may be pushed when the edges of the blanks pass them to snap under them.

As illustrated by Figures 16 and 17, accurate folding is further ensured by the guide strips 80 which are fixed in such lateral positions that their 15 thin outer edges are in alignment with the crease lines of the blanks on which the described folding is effected. When said folding is finished, during the temporary stopping of each blank, the timing of operation is such that as the folder plates 20 83 start to rise from the position shown in Figure 17, the blank-pushing chains 56 begin to travel and then move at accelerated speed toward the taping mechanism to be described. To prevent the edges a^2 from rising materially from the Figure 25 3 position, said edges pass first under the inclined portions 101 and then under the horizontal portions 102 of guide strips attached to both side faces of the aliner 98 (Figs. 1, 7, 28).

As has been described, the shaft 53 carries, between the sprockets 54, an intermediate sprocket 55 (Fig. 23), but in practice I preferably employ two such sprockets. Although the drawings illustrate but one such sprocket 55, and a chain 103 driven thereby, the illustration of the one will 35 suffice for the two. Each of such two chains carries individual pushing lugs 104 and travels to and is supported by an idly mounted sprocket 105 (Fig. 7) located at a point where the pushers 104 will engage the blanks after leaving the feeding mechanism to be described and just before said blanks pass under the aliner 98. The purpose of such chains and lugs will now be described.

Sometimes there is a tendency of the free ends 45 of the blanks to drag back while the blanks are being advanced by the pushers 51 of the main chains 56. By the term free ends, I mean those end portions of the blanks the edges of which are to be brought into juxtaposition when folded. The lugs 104 of the supplemental chains 103 are 50 in lateral alignment with the lugs 57 of the main chains 56 (Figs. 5 and 21). This provides a series of pushing lugs some of which engage the rear edges of the bodies of the blanks and other simultaneously engage the rear edges of the top or 55 free end portions of the blanks when the latter are folded over to abutting relationship. Consequently, if there is any such friction of the edges of the blank with the sides of the aliner 98 as the folded blanks are moving along, as might cause a 60 backward drag, the laterally aligned lugs 104, 57, ensure forward movement to the taping mechanism in squared up proper condition. To secure this result, it is essential that the lugs of all 65 of the chains shall be independent of each other.

The taping mechanism will now be described.

Mounted on the cross bars 95 (Figs. 23 and 28) is a bracket 106 having a vertical wall portion 107. An apertured lug of the bracket is engaged by a screw rod 108 to effect lateral adjustment of 70 the bracket and all members carried thereby. Secured to the wall 107 and rising therefrom is an upright 109 carrying a spindle for a reel 110 of adhesive tape b.

Also secured to the bracket wall is a tape- 75

storage box or casing 111 (Figs. 1, 21, 23, 27, 28). From the reel, the tape passes between two rolls 112, 113, the upper one being carried by a stud shaft 114 mounted in bearings in a wall portion 5 of the box 111, said shaft also having a pinion 115 driven by an intermeshing pinion 116 (Fig. 21) carried by another stud shaft 117 which has a sprocket 118 engaged by a chain 119, said chain being engaged and driven by a sprocket 120 carried by a shaft 121. The shaft 121 (Fig. 23) is mounted at one end in a bearing in the wall 107 and is so connected to it that when the bracket 106 and its wall portion 107 are adjusted laterally of the machine, the said shaft 121 moves 15 in the direction of its length. Said shaft enters a tubular shaft 122 and is slidable therein and has spline connections therewith. The tubular shaft is mounted in bearings afforded by brackets 123 rising from a cross bar 95, and at its outer 20 end has a sprocket 124 connected by a chain 125 (Fig. 28) with a sprocket 126 carried by the shaft 53.

The lower roll 113 (Fig. 27) is idly mounted in an arm, or pair of arms, 127, pivoted at 128 to the box 111 and having a spring 129 connected to its outer end the tendency of which is to so hold the roll 113 against the driven roll 112 as to effect feeding of the tape *b*. A link 130 connects the pivoted arm 127 with the armature of an electric magnet 131 the circuit of which includes a mercury switch 132 of well-known type. Said switch 132 is mounted on a lever beam 133 of light material which is pivoted at 134 in the box 111.

35 So long as the lower roll 113 is held by the spring 129 in the position shown in Figure 27, the tape *b* continues to be drawn from the supply reel and is fed into the storage box 111 and accumulates on the beam 133 until enough has been 40 deposited thereon to overbalance the weight of the mercury switch 132 which is adjustable toward or from the pivot 134 to meet such conditions as differences in weight of selected grades of tape.

45 The reason for the employment of the mechanism just described (Fig. 27) is to enable tape to be drawn intermittently along for cutting and applying to the folded blank as presently described, without having the correctness of the 50 length of sections cut interfered with by such causes as slipping of the feed rolls and the gradually diminishing size of the supply roll of tape. It will now be understood that the preservation of a light accumulation of tape on the beam 133, 55 enables tape to be drawn out from the storage box intermittently as presently described, without encountering any such periodic resistance as might interfere with the accuracy of the lengths to be cut therefrom for application to the folded 60 blanks.

65 When the desired amount of tape accumulates on the beam, its weight causes the beam to swing down, and the mercury switch 132 closes the circuit of the magnet 131 so that a downward pull is exerted on the link 130 and the lower roll 113 is pulled away from the driven friction roll 112, and feed from the supply roll into the storage 70 box immediately ceases. Then when successive cutting of sections of tape reduces the accumulation in the box, the beam rises, the circuit is broken by the switch 132, and the spring 129 causes the roll 113 to again co-act with the roll 112 in feeding some more tape into the storage box.

75 From the box 111, the tape leads over a roll

135, then down and under a guide strip 136 (Figs. 28 and 29), then between upper and lower rolls 137, 138, then under a cutting knife 139, and then between rolls 140, 141, one of which moistens the under surface of each strip section 5 that is cut off by the knife. All of the rolls and knife members are supported by an extension portion of the bracket wall 107. A water holding bath 142 into which the roll 141 dips is supported by an arm 143 extending down from the bracket 10 106 (Fig. 26). In practice the roll 141 is felt covered.

15 As shown in Figure 29, a strip 144, supported by the transverse strip 136, extends down between the feed rolls 137, 138, the upper one of 15 which has a circumferential groove to accommodate said strip 144 the purpose of which is to facilitate the proper introduction of the end of a tape that is being installed in the machine.

The upper roll 137 is carried by the shaft 154 20 which is driven intermittently, and the extent of each partial rotary movement is controlled by mechanism that will be presently described, said mechanism including means for adjusting it to provide for cutting the tape into accurate 25 lengths according to the sizes of the containers (Fig. 4) being produced.

From the rolls 137, 138 (Fig. 29) the tape *b* passes between transverse shearing members one of which consists of a knife 139 pivoted at 145 30 (Fig. 23) to the bracket 106 and connected by a link 146 to a lever 147 pivoted at 148 to the bracket wall 107 (Fig. 21), a spring 149 being connected to the other end of the lever. Between the said end and the pivot 148, the lever 35 has a roll 150 contacting with a cam disk 151 carried by the shaft 121, said disk having a recess, indicated by dotted lines in Figure 21, into which the roll 150 can drop momentarily to permit the spring 149 to so actuate the lever 147 40 as to effect a quick operation of the knife 139.

45 The tape-moistening roll 141 is rotated in the proper direction by a crossed belt 152 (Fig. 28) mounted on a small pulley carried by the shaft of said roll and a larger pulley 153 carried by a 45 shaft 154 (Fig. 23) mounted in the side frame members and having a pinion 155 mounted on one end. An intermediate pinion 156 (Fig. 21) meshes with the pinion 155 and a gear 157 of a shaft 158 which is driven as hereinafter described.

50 The water bath 142 is supplied with water by suitable means such as a bottle 159 (Figs. 25 and 26) supported by a bracket 160 attached to the wall 107, a pipe 161 connecting the bottle and 55 the said bath. Of course in practice, suitable well-known means not necessary to illustrate, are employed to maintain the water at proper level in the bath.

55 The blanks, in the folded condition illustrated 60 in Figure 3, are supplied by the pushing chains in time with the feed and cutting of the tape, and each moistened section of tape is delivered onto a folded blank in the position illustrated in Figure 4. The so-assembled tape sections and 65 folded blanks immediately pass to suitable pressing and stacking mechanisms. In the drawings I illustrate, without being limited thereto, upper and lower belts 162, 163, between which the folded blanks, with tape sections attached thereto, pass. 70 The upper belt 162 passes around a pulley 164 carried by the shaft 158, and the lower belt passes around a pulley 165 of a lower shaft 166 (Figs. 21, 28). The two shafts 158, 166, are provided with intermeshing gears, and the belts are 75

kept under proper tension and are subject to suitable pressing rolls carried by suitable frames 167.

An important feature of my invention consists in mechanism whereby, if no folded blank is arriving in position to be taped, there will be no operation of the tape feeding members, and consequently no liability of moistened tape sections clogging up the machine. Said mechanism 10 will now be described:—

Referring to Figures 21, and 23, a vertically slidable rod 168 is mounted in guiding brackets 169 projecting from the frame of the machine and has a roll 170 riding on a cam 171 carried 15 by a short shaft 172 having a sprocket 173 engaged by a chain 174 which is driven by a sprocket 175 carried by shaft 37. Said chain also engages a sprocket of shaft 93. The three shafts 37, 93 and 172 are therefore driven constantly at 20 uniform speed. The slide 168 is not permanently connected to anything else, but its upper end has a recess 176 (Fig. 22).

Above the slide 168 and in line with it, is a slide 177 one of the guides for which is shown 25 at 178. Pivoted to the lower end of the slide 177 is a link-shaped lug 179 a cross pin 180 of which is adapted to fit the recess 176 of the lower slide at certain times as will be described. In line with the axis of the pin 180 is a roll 181. A 30 flat spring 182 secured to the guide lug 178 tends to maintain the link lug 179 in its relative position shown in Figure 21, but, as will be explained, said lug is swingable away from alinement with the slide 168.

The upper end of the slide 177 is connected by 35 a link 183 with the middle of a toggle 184 which connects the frame wall with the lower end of a lever 185 pivoted at 186 to a fixed bracket, a spring 187 being connected to the lower end of said lever. The upper end of said lever is yoke-shaped and 40 engages pins projecting from the hub 188 of a disk 189 splined to the shaft 154 so as to be rotatable therewith but shiftable along it. The disk 189 has a friction facing 190, and the constantly driven pinion 155 which is free on the 45 shaft 154, has a disk 191 fixed to it which coacts with the friction-faced disk 189 as a clutch.

To actuate the swinging lug 179, at times, out of alinement with the slide 168, a small rock 50 shaft or rod 192 is mounted in the frame. Its outer end has an arm 193 extending past and adjacent to the roll 181 of the lug 179. Its inner end has an arm 194 to which a spring 195 is connected, and another arm 196 connected by a link 197 to an arm 198 of a slender rock shaft 199. At the inner end of the rock shaft, near the mid-width of the machine, is a finger 200 which normally lies with its upper portion in the path of the folded blanks being carried to the taping 55 mechanism by the pushing chains.

The slide 177 has a roll 201 acted upon by a cam 202 carried by the shaft 53.

The mechanism just described is for the purpose of automatically controlling the tape feed 65 so that the tape is fed and a proper length thereof is cut off, only if a folded blank is approaching position to have a tape section applied thereto. If no approaching blank presses the finger 200 down, the disks 189, 191, remain separated and 70 the described gearing which actuates the tape-feeding roll 137 (Fig. 29) remains idle. But when a folded blank actuates the finger 200 it effects a pulling of the arm 194 away from the roll 181 of the lug 179 so as to permit the spring 75 182 to swing said lug so that the lower end of the

latter occupies the position shown in Figure 21. Then the slide 168 is pushed up by the action of the revolving cam 171, resulting in forcing the slide 177 up and, through the mechanism described, so actuating the clutch member 189 as 5 to result in feeding the tape. Later downward movement of the slide 177, is effected by the cam 202 acting on the roll 201 of said slide 177.

In order to properly feed the stiff corrugated paper blanks to attain accurate folding by the 10 mechanism that has been described, I have provided the improved means which will now be described.

Supporting the margins of the lower one of a pile of blanks *a* are strips 204. An intermediate 15 strip 205 (Figs. 5, 6 and 8) supports the middle portions of the pile. The strips 204 are carried by the inner faces of two upright walls 206 and extend over one of the cross bars 62. Hub portions 207 of the walls have threaded apertures 20 fitting a right and left hand threaded shaft 208 for effecting adjustment of the said walls which maintain the pile of blanks between them.

A gate strip 209 (Figs. 6, 7, 12 and 14), below the lower end of which the bottom blank is to be 25 fed by the pushing chains, is slidably mounted between ways 210 secured to one of the cross bars 65. Its vertical position is adjustably effected by a pin 211 (Figs. 12 and 14) rotatably mounted in a lug 212 of the gate strip and having a threaded lower end entering a threaded socket in a fixed cross bar 213. Said screw is for adjusting the gate strip to vary the space below its lower end to suit the thickness of the blanks being operated upon. 35

Mounted in a guideway in cross bar 65 (Figs. 14 and 15) is a slide 214 the lower portion having a recess in which is a block 215 having a serrated face to engage the front edges of the lower blanks of the pile. Pins 216 passing through inclined 40 slots in the block 215 enter the lower portions of the slide 214. A spring 217 tends to hold the block 215 up so that its serrated face projects slightly from the inner face of the strip 209.

The upper end of the slide 214 has a lug 218 45 which receives a pin 219 of an arm 220 of a rock shaft 221 supported by brackets 222 (Figs. 8 and 14) secured to cross bar 65. The rock shaft has another arm 223 (Figs. 8 and 12) connected by a link 224 with a lever 225 pivotally supported at 50 226 and having a roll 227 engaging a cam 228 carried by the shaft 74. The said cam, through the parts just described, causes the slide 214 to reciprocate vertically so that the serrated pusher foot 215 acts on the lower blanks to depress the 55 forward edges thereof to ensure the lower-most blank being in the plane of the opening or gate below the strip 209. While similar mechanism has been employed in feeds for other types of box blanks than corrugated sheets, it is important 60 in connection with the mechanism now to be described, for acting on the rear edges of the blanks, because of the natural tendency of corrugated paper to deflect from a flat plane.

To effect downward urging of the rear edges 65 of the corrugated paper blanks, to ensure positive proper engagement thereof by the pushers 57 of the carrier chains, I employ two rolls 229 (Figs. 5, 6, 9, 10 and 11), preferably of elastic material such as rubber, and peripherally ribbed or roughened. Said rolls are located directly above the line of travel of the pushers 57. Each is adjustable forward or back to suit the sizes of blanks 70 to be operated upon. Both are alike and a description of one will suffice for both. 75

Each roll 229 is mounted on and between two collars 230, 231, (Fig. 11) carried by a shaft 232 mounted in bearings 233, 234, of a horizontally U-shaped portion 235 of a bracket 236 mounted on a rib 237 secured to a wall member 60.

One end of the shaft 232 enters a screw plug 238 between which and the collar 231 is a spring 239. By adjusting the plug 238, the collar 231 can be caused to exert more or less yielding pressure against the roll 229 to vary the frictional grip of said roll between the two collars 231, 230.

To provide for holding the roll 229 in a position forward or back on the rib 237 of the wall member 60, to suit the size of the blanks operated upon, a stem 240 extends through the bracket 236, said stem having a threaded inner end engaging a gripper block 241. By means of a handle stick 242 carried by the outer end of the stem 240, the block 241 is caused to grip the upper flange of the fixed rib 237 and so maintain the bracket 236, 235, and the members carried thereby in desired position along the rib 237.

A sleeve or tubular shaft 243 is mounted rotatably on the stem 240 and has a pinion 244 and a sprocket 245. The pinion 244 meshes with a pinion 246 secured to the shaft 232, and the teeth of the sprocket 245 engage the chain 69. Therefore the travel of the two chains 69 effects, through the gearing described, frictional rotation of the two rolls 229 in a direction to urge the rear edges of the blanks downward for the purpose hereinbefore described.

To aid in maintaining the blanks in the proper condition of a pile, especially when the blanks are being deposited in place to be fed, each bracket 236 has secured to it an upwardly projecting guide strip 247.

The cam 202 (Figs. 21 and 23) which acts on the roll 201 of the slide 177, is carried by one end of a shaft 248 extending through the tubular shaft 53 and having at its other end a hand wheel 249 (Fig. 1) and a slotted segment 250. By means of said segment, the inner shaft 248 can be rotatably adjusted relatively to the tubular shaft 53, so that the cam 202 of shaft 248 will act on roll 201 of the upper slide 177 to stop the feed and effect cutting of the tape at the proper time. That is, said action of the cam 202 effects releasing of the clutch 190, 191.

It is to be understood that, during each cycle of operation, the cam 171, acting at the proper time on the roll 170 of the lower slide 168, effects the return of the clutch members to operative condition, ready to start the feed of the tape at the proper time.

When the blanks leave the feed mechanism, and stop in position to be folded, as has been described, if the blanks are wide but short in length, there is liability of the folding being somewhat askew. To effect perfect folding it is desirable to employ supplemental means, such as guides 251 (Figs. 1 and 7) having inclined faces, said guides being carried by a strip or strips 252 supported by the T bar 96, said strips being slotted to enable the guides to be accurately adjusted so that, when a blank is being folded the rear edges of its folded portions will glide down the inclined faces of the guides and be slightly urged forward if necessary.

As the operations of the different parts of the machine have been described in connection with the descriptions of the structure thereof, a description of the operation of the machine as a whole is unnecessary.

All parts of the machine are, of course, so adjustable, most of them by right and left hand screws, as to provide for acting on blanks of widely different sizes or shapes. As no claims thereto are made herein, detailed description thereof is unnecessary although the necessary parts are illustrated.

Most of the necessary gearing, as by shafts with sprockets, and connecting chains, has been described; but some of such gearing illustrated is so obvious as to need no specific description, especially in view of the fact that other specific types for gearing the operative parts together might be employed.

Having now described my invention, I claim:—

1. A blank folding machine having carriers for the blanks, folders for turning side portions of the blanks toward each other, and mechanism for causing the carriers to travel at diminishing speed followed by accelerated speed with intermediate stoppages to temporarily arrest movement of the blanks during operative movement of the folders.

2. A blank folding machine having a supply feed, traveling carrier mechanism for forwarding blanks at high speed from the supply feed, means for intermittently slowing down and arresting the speed of travel of said carrier mechanism, and folders in position to operate on the blanks while arrested.

3. A machine for folding creased blanks, having a feeder for the blanks, carriers for advancing the blanks singly from the feeder, rolls for acting on each blank leaving the feeder to compress it along two of its creased lines, said rolls being of a width to effect compression along both sides of the creases of the blanks, inwardly swinging folders for operating on side portions of each blank to fold them on their creased lines.

4. A blank folding machine having carriers for pushing blanks along at varying speeds including diminishing and accelerated speeds with intervening timed periods of rest, and folders in position to act on each blank during its period of rest.

5. A blank folding machine having carriers for pushing blanks along at varying speeds including diminishing and accelerated speeds with intervening timed periods of rest, folders for bringing the side edges of each blank into abutting relationship during its period of rest, and means for adhesively securing a section of tape across said edges.

6. A machine for folding creased blanks, said machine having blank-pushing mechanism, a pair of rock shafts mounted at opposite sides of the pushing mechanism and having folders for converting the blanks from flat to folded form, and means for imparting to the blank-pushing mechanism diminishing and accelerated speeds of travel with intervening timed periods of rest during the operation of said folders.

7. A machine for folding creased blanks, said machine having blank-pushing mechanism, a pair of rock shafts mounted at opposite sides of the pushing mechanism and having folders for swinging side portions of the blanks up and inward toward each other, a stationary aliner in position for the edges of the inwardly folded portions to contact therewith, and means for causing the blank-pushing mechanism to travel at diminishing and accelerated speeds with intervening timed periods of rest during the operation of said folders.

8. A blank-folding machine having a stationary vertical member for alining meeting edges of folded blanks, means for causing blanks to pass under said aliner, and folding mechanism for swinging side portions of the blanks to cause the edges thereof to approach the aliner, said aliner having yieldable catches to prevent the edges of said side portions of the blanks from lifting after being folded.
9. A folding machine having means for causing blanks to travel, a stationary vertical plate under which the blanks pass, and means for folding the blanks and swinging edge portions thereof toward said plate, the said plate having yieldable means for catching the said edge portions.
10. A folding machine having means for causing blanks to travel, a stationary vertical plate under which the blanks pass, and means for folding the blanks and swinging edge portions thereof toward said plate, the said plate having yieldable means for catching the said edge portions, and also having guide strips on its side faces to prevent said edge portions of the blanks from rising when the blanks continue movement after being folded.
11. A machine for folding corrugated paper blanks, said machine having a support for a pile of blanks, chains provided with individual pushing lugs for engaging the rear edge of each successive bottom blank and carry it through the machine, folding mechanism for bringing the side edges of each blank close together while at an intermediate point of its travel, and individual travelling lugs between the first mentioned lugs for engaging the rear edges of the folded side portions of the blanks.
12. A machine for folding corrugated paper blanks, said machine having a pair of main chains provided with individual pushing lugs for engaging the rear edges of the bodies of the blanks, means for folding side portions of the blanks onto the bodies thereof, and an intermediate pair of shorter chains provided with individual pushing lugs for engaging the rear edges of the folded side portions of the blanks.
13. A machine for folding corrugated paper blanks, said machine having a pair of main chains provided with individual pushing lugs for engaging the rear edges of the bodies of the blanks, means for folding side portions of the blanks onto the bodies thereof, and an intermediate pair of shorter chains provided with individual pushing lugs for engaging the rear edges of the folded side portions of the blanks, the lugs of all of the chains being in lateral alinement.
14. A machine for folding corrugated paper blanks, said machine having a pair of main chains provided with individual pushing lugs for engaging the rear edges of the bodies of the blanks, means for folding side portions of the blanks onto the bodies thereof, and an intermediate pair of shorter chains provided with individual pushing lugs for engaging the rear edges of the folded side portions of the blanks, the lugs of all of the chains being in lateral alinement and the lugs of the intermediate chains being permanently higher than the lugs of the said main chains.
15. In a machine for folding blanks and applying sections of tape thereto, a support for a supply reel of tape, means for drawing the tape from the reel and effecting an accumulation thereof, means for drawing the tape from said accumulation to be cut into sections and applied to folded blanks, and means controlled by said accumulation for starting and stopping the means for drawing the tape from its supply reel.
16. In a machine for folding blanks and applying sections of tape thereto, a support for a supply reel of tape, a pivoted support for an accumulation of tape, feed mechanism for drawing tape from the reel and depositing it on said pivoted support, a second feed mechanism for drawing tape from said pivoted support, and means connected with the pivoted support for controlling the first-mentioned feed mechanism.
17. In a machine for folding blanks and applying sections of tape thereto, a support for a supply reel of tape, a pivoted support for an accumulation of tape, feed mechanism for drawing tape from the reel and depositing it on said pivoted support, a second feed mechanism for drawing tape from said pivoted support, an electric magnet for controlling the first-mentioned feed mechanism, and a switch for the circuit of said magnet, said switch being actuated by the pivoted support for said accumulation.
18. In a machine having means for folding blanks to flat condition with abutting edges, means for securing said edges together by means of adhesive tape, said means including a tape-feeding roll, a tape-severing knife, means for moistening each section after it is cut to proper length, whereby moisture is applied to the sections only after they are cut, and means for automatically controlling the operation of the feeding roll by the approach of a blank to have a tape section applied to it.
19. In a machine having means for folding blanks to flat condition with abutting edges, means for securing said edges together by means of adhesive tape, said means including a tape-feeding roll, a tape-severing knife, means for moistening each section after it is cut to proper length, means being provided for adjusting the timing of operation of the feeding roll to vary the lengths of the cut sections of tape, and means for automatically controlling the operation of the feeding roll by the approach of a blank to have a tape section applied to it.
20. In a machine having means for folding blanks to flat condition with abutting edges, means for securing said edges together by means of adhesive tape, said means including a tape-feeding roll, a tape-severing knife, means for moistening each section after it is cut to proper length, means being provided for operating the feed of the tape in timed relationship with the travel of each folded blank to be taped, and means including a yieldable member in the path of blanks approaching the feeding roll for controlling the operation of said rolls.
21. In a machine for folding corrugated paper blanks, a holder for a pile of blanks, blank-carrying means mounted to travel under said pile holder, and means for urging downward both the front and rear edges of the lower blanks of the pile.
22. In a machine for folding corrugated paper blanks, a holder for a pile of blanks, blank-carrying means mounted to travel under said pile holder, and means for urging downward both the front and rear edges of the lower blanks of the pile, the urging means for the front edges of the blank comprising a vertically movable slide having a serrated block yieldingly carried by its lower end.
23. In a machine for folding corrugated paper blanks, a holder for a pile of blanks, blank-carrying means mounted to travel under said pile hold-

er, and means for urging downward both the front and rear edges of the lower blanks of the pile, the urging means for the rear edges of the blanks comprising frictionally-driven rolls.

5. 24. In a machine for folding corrugated paper blanks, a holder for a pile of blanks, blank-carrying means mounted to travel under said pile holder, and means for urging downward both the front and rear edges of the lower blanks of the pile, the urging means for the rear edges of the blanks being adjustable relatively to the urging means for the front edges.

15. 25. In a machine for folding corrugated paper blanks, a holder for a pile of blanks, blank-forwarding chains provided with pushing lugs mounted to travel under said pile holder, and means for urging downward both the front and rear edges of the lower blanks of the pile, the urging means for the rear edges of the blanks

comprising frictionally-driven rolls each of which is directly above the line of travel of a lug-carrying chain.

26. In a machine for folding corrugated paper blanks, a holder for a pile of blanks, blank-forwarding chains provided with pushing lugs mounted to travel under said pile holder, frictionally-driven rolls above said chains to urge downward the rear edges of the blanks, and gearing between said rolls and chains to effect actuation of said rolls by the chains. 10

27. A blank folding machine having carriers for the blanks, folders for turning side portions of the blanks toward each other, mechanism for temporarily arresting the carriers during operative movement of the folders, and stationary inclined guides in position to urge the folded side portions of the blanks forward. 15

MELVIN H. SIDEBOOTHAM.
